J. A. BRILL & W. S. ADAMS.
MOTOR TRUCK.

No. 547,476.

Patented Oct. 8, 1895.

UNITED STATES PATENT OFFICE.

JOHN A. BRILL AND WALTER S. ADAMS, OF PHILADELPHIA, PENNSYLVANIA.

MOTOR-TRUCK.

SPECIFICATION forming part of Letters Patent No. 547,476, dated October 8, 1895.

Application filed January 3, 1894. Serial No. 495,547. (No model.)

To all whom it may concern:

Be it known that we, JOHN A. BRILL and WALTER S. ADAMS, citizens of the United States, residing at Philadelphia, in the county 5 of Philadelphia and State of Pennsylvania, have made certain new and useful Improvements in Motor-Trucks, of which the following is a specification.

This invention has reference more particularly to the class of trucks that have pivotal side bearings for the car-body, and one object of the invention is to provide an improved construction of axle-box frame, whereby means are provided for guiding the car-body 10 side-bearing posts, as well as for connection with the means for drawing between the car-body and the axle-box frame. For this purpose the axle-box yokes are connected with bars or extensions that lie over the side bars 15 of the axle-box-frame side bars, and said extensions are connected by a cross bar, with which a drawing device is connected with the car-body or its sill. Said drawing device preferably consists of an equalizing-bar pivoted 20 on said cross-bar and pivotally connected at its ends by links or bars with the car-body or a sill thereof. By this means the pivotal drawing point between the axle-box frame and car-body may be located where desired without disturbing the actual pivotal center of the 25 truck, while the proper disposition of the weight of the car-body to obtain a maximum traction is retained, the action of the drawing devices being positive in all positions of the parts. The cross-bar of the axle-box yokes 30 also provides means for the suspension of the motor. With this construction, also, the weight of the car-body is borne between a pair of wheels and the pivotal center of the 35 truck whereby the truck is properly held on the tracks and pounding of the wheels is avoided.

The invention further consists in the novel 40 details of improvement and the combination 45 of parts that will be more fully hereinafter set forth and then pointed out in the claims.

Reference is to be had to the accompanying drawings, forming part hereof, wherein—

Figure 1 is a plan view of our improved 50 truck, a portion of the car-sills being shown

in position, and Fig. 2 is a partly-broken side elevation thereof.

In the accompanying drawings, in which similar numerals of reference indicate corresponding parts in both views, the truck is 55 shown provided with large driving-wheels 1 and smaller trailing wheels 2.

3 represents the axle-box-frame side bars, 4 the axle-box yokes for the driving-wheels 1, and 5 the yokes for the axle-boxes of the 50 wheels 2, the yokes 4 and 5 being connected with the side bars 3, as shown, or in any desired manner.

6 represents extensions from the yokes 4, 6 and 7 is a cross-bar connecting said extensions. 65 8 are extensions from the yokes 5, and 9 is a cross-bar connecting said extensions 8, the parts 3, 4, 5, 6, 7, 8, and 9 together forming the axle-box frame.

As shown in Fig. 2, the lower part of the 70 upright 4^a of the yoke 4 is connected with the end of the side bar 3, and the upper part of the upright 5^a of the yoke 5 is connected with the opposite end of said side bar, whereby provision is made for the difference in height 75 of the axles 1^a 2^a of the wheels 1 2. From the upper parts or tops of the yokes 4 extend bars or extensions 10, that lie over the side bars 3 and extend parallel therewith, as shown. The ends of the extensions 10 are 80 connected by a cross-bar 11, as shown in Fig. 1, and by preference the axle-box frame, extensions 10, and cross-bar 11 are made in a homogeneous piece of metal, as by forging, whereby a firm solid structure is provided. 85 With the cross-bar 11 drawing devices are connected that also connect with the car-body or one of its sills, and these devices are so organized that a direct pull will be effected between the car-body and the truck in all positions of the latter relatively to the car-body. 90

In our improvement the drawing devices extend from opposite sides of the car-body near to the truck center, and for this purpose we have provided an equalizing lever or bar 12 95 that is centrally pivoted by a pin 13 on the cross-bar 11, said pivot lying in the longitudinal center of the truck. (See Fig. 1.) The ends of the equalizing-lever 12 are pivotally connected with rods or draw-bars 14 14, that at 100

their outer ends are pivotally connected with the car-body or a cross-sill 15 thereof, preferably over or near the axle of the driving-wheels. One end of each rod 14 is preferably 5 forked, as at 16, to straddle the lever 12, pivot-pins 17 passing through said forks and through said lever, whereby the lever 12 and rods 14 are pivotally connected. (See Fig. 2.) The forks 16 are shown wider than the thickness 10 of the lever 12, and the pivot-pins 17 are loosely connected with said forks, whereby freedom of movement or play is allowed between said parts to permit up-and-down motion of the car-body relatively to the truck; 15 but of course any desired means may be provided for this purpose.

The pivotal arrangement between the ends of the rods 14 and the car body or sill 15 may be suitably organized. We have shown pivots or pins 18 depending from plates 19, secured to the sill 15 by bolts 20, said pivots passing through the rods 14 and secured by pins or cotters 21. By the above construction the drawing will take place between the 25 car-body and truck from a point in the longitudinal center of the truck to the sides of the car-body, through the medium of the cross-bar 11, equalizing-lever 12, and rods 14, and as the truck and car move relatively to each 30 other the lever 12 and rods 14 will assume the necessary positions, the lever 12 suitably turning on its pivot 13 to provide for the various movements of the car and truck. With this device the proper and positive drawing takes 35 place, also, during the canting or swaying of the car and truck, the looseness of the pivots allowing for such motions without undue strain on the parts. The same looseness of connection between the pivots 18 and bars 14 40 can be had, if desired.

It will be apparent that a device constructed as above set forth will afford a maximum of efficiency under all conditions, and that by having the cross-bar 11 situated at a distance 45 from the wheels, and elevated above the side bars 3 3 of the axle-box frame a large and unobstructed space is afforded for the location of a motor or the grip devices for a cable-car.

The car-body may be sprung and pivotally 50 supported on the truck or axle-box frame in any suitable or desired manner—for instance, as shown in the patent to W. S. Adams, No. 538,857, dated May 7, 1895, which is as follows: At 25 are cradles suitably supported on 55 the side bars 3 3 of the axle-box frame adjacent to the yokes 4, which cradles are provided with the recessed lugs to receive spring-posts 26 26. The posts 26 also pass freely through apertures 27 in the extensions 10, 60 whereby they are guided, and said posts are connected by a bearing 28 that engages a depending and segmental plate 29, carried by the car-body or its longitudinal side sills 30, as more fully set forth in said patent. 65 At 31 are coiled springs surrounding the posts 26 and resting on the cradles 25, a suit-

able plate 32 resting on said springs and lying beneath the extensions 10. The posts 26 have suitable enlargements at their upper parts that rest on the plate 32, whereby the weight of the car-body is transmitted to said springs. It will be observed that the cross-bar 11 that connects the extensions 10 acts as a brace between the outer ends of said extensions, and thereby greatly strengthens the 70 parts, and the lateral strain of the posts on said extensions is reduced and danger of bending or breaking of said extensions is avoided.

It will be seen that the weight of the car-body is sustained on the axle-box frame between the yokes 4 5 and close to the large driving-wheels, whereby the weight is properly distributed on the axle-box frame and pounding of the wheels is avoided, and that 85 the drawing devices are located at the center of the truck, and the power is directly transmitted therefrom to the axle-box yokes and thus to the large wheels. This feature will be found of great utility in that the main 90 parts of the axle-box frame are not directly utilized for drawing purposes, but are left free at all times to sustain the superposed weight without rendering extra work.

The brake mechanism, which is not claimed 95 herein, but which is particularly adapted for use on this class of truck, is organized as follows: 35 are standards on the cross-bars 7 9 of the axle-box frame, and from these standards depend pivoted links 36, that are pivoted 100 to the brake-shoes 37 38, which are thus sustained in proximity to the wheels 1 2. The brake-shoes 37 are connected by a brake beam or bar 39, and the shoes 38 are connected by a similar beam or bar 40. To the beam or 105 bar 40 are connected levers 41, that extend upwardly and inwardly and are connected at their upper ends by an equalizing-bar 42. This bar 42 is made segmental at its central portion 43, the segmental portion 43 of said 110 bar being united to inwardly-inclined members 44 at the outer ends of said equalizing-bar. By this means the segmental portion of the bar 42 is provided for without unduly increasing the transverse width of said bar 115 between its ends, or, in other words, a narrow bar is provided having a segmental portion. This segmental portion 43 of the bar 42 is movably connected with a draw-bar 45 (shown provided with a forked end 46 to straddle the 120 bar 42) and a friction-roller 47 to engage said bar, whereby the draw-bar 45 may slide on the bar 42, or vice versa. The draw-bar 45 may be connected with any suitable brake-actuating devices to actuate and apply the 125 brake-shoes to the wheels by the drawing-bar 42 laterally. The brake-beams 39 and 40 are connected together by rods 48, that lie close to the inner sides of the wheels, and said rods 48 may be provided with turnbuckles 49 to 130 regulate the length of said rods. In order to allow the rods 48 to lie as low as possible in

the truck and at the same time have proper connection with the levers 41, said rods have a downward bend at 50 close to their point of pivotal connection 51 with the beam 40. When 5 the bar 42 is drawn upon, the levers 41 will be turned and thus press the shoes 38 against the respective wheels, and the rods 48 will be drawn to press the shoes 37 against the wheels 1.

10 It is apparent that the devices for connecting the car and truck together for traction can be used in a truck not provided with the particular form of frame herein described, nor is it limited to the other peculiarities of 15 the truck.

Having now described our invention, what we claim is—

1. The combination, with a car body, of a truck having an axle box frame having side 20 bars with axle box yokes, extensions from the yokes, a transverse bar connecting said extensions, and drawing devices pivotally connecting said car body with said cross bar, substantially as described.

25 2. An axle box frame having side bars, yokes therein, extensions from said yokes lying over the side bars, a transverse cross bar connecting said extensions, a bar pivotally secured to said cross bar, and connections 30 from said last mentioned bar for attachment to a car body, substantially as described.

35 3. A car truck having an axle box frame with side bars included therein, axle box yokes in the side bars, a cross bar rigidly connecting the yokes, combined with a car body, and pivotal drawing devices extending from points near the sides of said car body to the central portion of said cross bar, substantially as described.

40 4. An axle box frame having side bars, axle box yokes, extensions from the yokes, and a cross bar connected with said extensions, combined with an equalizing lever pivotally connected with said cross bar, rods pivotally connected with said lever, and a car body pivotally connected with said rods, substantially as described.

45 5. An axle box frame having side bars, axle box yokes, extensions from the yokes, and a cross bar connected with said extensions, combined with an equalizing lever pivotally connected with said cross bar, a car body, and pivotal devices connecting said car body with said lever on opposite sides of its pivot, substantially as described.

55 6. The combination of an axle box frame having side bars, axle box yokes, extensions from the yokes, and a cross bar connected with said extensions, with an equalizing lever cen-

trally pivoted to said cross bar, rods pivotally connected with said lever and having free vertical motion on their pivots, and a car body pivotally connected with said rods, substantially as described.

7. The combination of an axle box frame 65 having side bars, axle box yokes, extensions from the yokes, and a cross bar connected with said extensions, with an equalizing lever pivotally connected with said cross bar, forked rods pivotally connected with the ends of said lever, and a car body pivotally connected with said rods, substantially as described.

8. The combination with an axle box frame having side bars, axle box yokes, extensions from said yokes lying over said side bars, and a cross bar connecting said extensions, of an equalizing lever centrally pivoted to said cross bar, rods pivotally connected with the ends of said lever, and a car body pivotally connected with said rods, substantially as described.

9. An axle box frame having side bars, yokes, extensions from said yokes lying over said side bars, and a cross bar connecting said extensions, combined with spring supported 85 bearing posts guided by said extensions and supported by said side bars, a car body, and pivotal bearings between said posts and said car body, substantially as described.

10. An axle box frame having side bars, axle 90 box yokes, extensions from the yokes lying over the side bars, a cross bar connecting said extensions, combined with spring supported posts guided by said extensions and supported by said side bars, a car body, connections on 95 the cross bar for attachment to the car body, and pivotal bearings between said posts and car body, substantially as described.

11. The combination of an axle box frame having side bars, yokes, extensions from said 100 yokes lying over said side bars, and a cross bar connecting said extensions, with posts guided by said extensions, a cradle or support carried by said side bars and receiving said 105 posts, springs around said posts, a plate resting on said springs and arranged to receive the thrust of said posts, a car body, bearings on the posts, and restraining plates on the car body, substantially as described.

Signed at New York, in the county of New 110 York, and State of New York, this 30th day of December, 1893.

JOHN A. BRILL.
WALTER S. ADAMS.
